JAMES W. PATERSON, OF CHICAGO, ILLINOIS, ASSIGNOR TO CURTAIN SUPPLY COMPANY, OF CHICAGO, ILLINOIS, A CORPORATION OF NEW JERSEY.

CURTAIN-FIXTURE.

SPECIFICATION forming part of Letters Patent No. 754,404, dated March 8, 1904.

Application filed August 1, 1901. Serial No. 70,477. (No model.)

To all whom it may concern:

Be it known that I, JAMES W. PATERSON, of Chicago, county of Cook, and State of Illinois, have invented certain new and useful 5 Improvements in Curtain-Fixtures, of which the following is a specification.

This invention relates to that class of curtain-fixtures wherein the lower margin of the shade is provided with spring-actuated friction-shoes serving to restrain the shade against the tendency of its winding-up spring. The construction is such that the friction device is rendered operative mainly by the upward pull of the curtain-roller spring and is 15 released by a downward pull upon the curtain itself.

In the drawings, Figure 1 is a sectional elevation through the curtain-stick, showing the holding device arranged therein. Fig. 2 is a 20 plan view of the curtain-stick, partly broken away and showing the holding device in edge view. Fig. 3 is a detail showing an operating mechanism for the holding devices, and Fig. 4 is a detail showing the shoe in the 25 release position.

In the drawings let 5 represent a flexible curtain or shade, which, it is to be understood, will be mounted upon a spring-actuated shade-roller. (Not shown.) In the lower 30 margin of the shade is mounted a suitable tube or hollow curtain-stick, which in the present illustration is shown as a flat tube, (marked 6.) Within the hollow of this curtain-stick and near its outer ends are slidably 35 and pivotally mounted the shoes 7, having friction-surfaces 8. The shoes 7 are shown as in the form of cams and as provided in the shank or body portion with a slot 9, through which a pin 10 passes, said pin being fixedly 40 secured in the shade-stick. This slot-and-pin connection renders the shoes capable of slight endwise as well as a rocking motion, which gives them a cam action and affords the necessary adjustability to variations in the window-frames. Rods 11 are loosely connected 45 to the shoes 7 by the pivots, (marked 12,) and these rods are surrounded by the springs 13.

The mechanism described is preferably duplicated in each end of the shade-stick, and

the rods 11 preferably extend inwardly to 50 near the middle of the stick and are provided with actuating devices whereby they may be retracted against the thrust of their controlling-springs. As shown, the rods have a threaded connection with the apertured plates 55 14, the apertured portions of said plates overlapping each other, and the operating-bolt 15 having cranks 16 lying within said apertures and engaging the walls thereof, the cranks being oppositely disposed, so that by rotation 60 of the bolt in one direction the rods are moved, the apertured plates sliding upon each other, and the friction-surfaces 8 may be positively withdrawn from contact with the bottoms of the grooves in the window-frame or 65 their frictional contact therewith so far reduced as to enable the curtain to be easily lowered. The ends of the tube 6 project into the groove to serve as guides, and it will be observed that the upper wall of the shade-stick is cut away, as shown at 6^a, and that the rear portion of the shoe 7 is rounded off. Various obvious changes can be made in connection with this guiding feature without departing from the invention. 75

As shown in Fig. 1, the friction-surfaces 8 are in contact with the window-frame, (indicated at 18,) the springs 13 affording sufficient pressure to maintain the shoes in holding position. If it be desired to adjust the curtain to a higher position, it can be forced up against the holding action of the shoes; but as such mode of adjustment would have a tendency to throw the shoes out of the groove the proper mode of operation is to retract the 80 shoes by operating the bolt 15, whereupon the curtain may be adjusted up or down, and when the bolt is released the springs will return the friction-shoes into contact with the window-frame and hold the curtain in the 85 adjusted position. In drawing the curtain down it is not necessary to retract the shoes. A pull on the bottom of the curtain will cause the heads to rock on pins 10, as indicated in Fig. 4, thus reducing the friction to a minimum, as 90 only the lower corners of the shoes would ride in contact with the grooves. The instant the curtain is released from the moving force the 95

shoes tend to rock into frictional engagement with the bottoms of the grooves. It may also be observed that this fixture may be operated in the same manner as various fixtures here-
5 tofore introduced by means of pendants or other retracting means, both in the upward and downward movement. In fact, in the usual types of devices of this character the release when the curtain is to be lowered is as
10 necessary as in the raising movement; but in my construction it is immaterial whether the force of the outwardly-thrusting springs be overcome when the curtain is to be drawn down. The general public operate these de-
15 vices carelessly, and to overcome the difficulty arising from their improper operation various means have been proposed and are largely in use for making the curtains automatically self-righting. While this curtain device is
20 not in the strictest sense self-righting, it is automatic in its operation, and the heads are not likely to be drawn out of the grooves by the improper action in lowering the curtain.

I have shown specific forms, but except
25 within the limits of the appended claims they are not essential to the invention.

I claim—

1. In a window-shade holder the combination with a casing and a spring-actuated shade, of a bar carried by the shade, a piv-
30 oted locking-cam at the end of the bar adapt-
ed to engage the casing above its pivoted

point, a rod carried by the bar and pivotally connected to the cam, a spring for normally forcing the rod outward to set the cam into 35 holding engagement with the casing, and means for retracting the rod.

2. In a window-shade holder the combina-
tion with a casing and a spring-actuated shade, of a bar carried by the shade having 40 ends extended to serve as guides, pivoted locking-cams at the ends of the bar, spring-actuated rods within the bar pivotally connected to the cams, and means for retracting the rods to release the cams from holding en- 45 gagement with the casing.

3. In a curtain-fixture for spring-actuated curtains a curtain-stick, shoes slidingly and pivotally mounted thereon, springs normally tending to thrust the shoes into contact with 50 the window-frame, and means for retracting said shoes, substantially as described.

4. In a curtain-fixture the combination with a curtain - stick of sliding, pivoted shoes, springs normally tending to thrust said shoes 55 into contact with the window-frame and the shoes being adapted to rock upon their pivots when the curtain is lowered whereby to release the curtain, substantially as described.
